ADJUSTABLE LOCKING DEVICE

Louis L. Deal, Rye, N. Y., assignor to Deal Slide-Lock Devices, Inc., New York, N. Y., a corporation of New York

Application December 31, 1946, Serial No. 719,393

13 Claims. (Cl. 192—8)

1

The present invention relates to locking devices and more particularly to a type of locking device which may be referred to as an adjustable slide lock, one example of which is shown in Re-issue Patent No. 20,327.

The present lock embodies features and advantages over the lock of said re-issue patent, and its use may be preferred in certain instances.

An object of the present invention is to provide a new and improved slide lock.

Another object of the invention is to provide a new and improved slide lock which may be readily adjusted to different positions.

Another object of the invention is to provide a new and improved slide lock adapted to be more securely locked in a desired position.

Still another object is to provide a new and improved slide lock adapted to readily operate along a curved path.

A further object is to provide a slide lock adapted to minimize the possibility of lost motion in the lock.

A still further object is to provide a new and improved engine controlling mechanism embodying the present slide lock.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a sectional view, partly broken away, showing a preferred embodiment of the invention;

Fig. 2 is a view taken along the line 2—2 of Fig. 1;

Fig. 3 is a plan view showing the slide lock illustrated in Fig. 1;

Fig. 4 is a plan view, partly broken away, of the slide lock shown in Fig. 3;

Fig. 5 is a view along the line 5—5 of Fig. 1;

Fig. 6 is a view along the line 6—6 of Fig. 1;

Fig. 7 is a view along the line 7—7 of Fig. 1;

Fig. 8 is an exploded perspective view illustrating another form of the invention;

Fig. 9 is a longitudinal sectional view showing the parts of Fig. 8 in assembled relationship;

Fig. 10 is a sectional view taken along the line 10—10 of Fig. 9;

2

Fig. 11 is a view showing the invention embodied with one form of controlling means;

Fig. 12 is a sectional view along the line 12—12 of Fig. 11;

5 Figs. 13 and 13a are exploded perspective views showing details of slide locks which may be embodied in the controlling means of Figs. 11 and 12;

Fig. 14 is a sectional view, partly broken away, 10 showing a modified form of the invention;

Fig. 15 is a sectional view illustrating the invention embodied in a lock adapted to travel in a curved path;

Fig. 16 is a view along the line 16—16 of 15 Fig. 15;

Fig. 17 is a view along the line 17—17 of Fig. 15; and

Fig. 18 is a perspective view illustrating a modified form of locking member.

20 Referring more particularly to Figs. 1 to 7, there is shown a plate or base member 1 having a lock 2 secured thereto. The lock 2 is shown generally in Fig. 3, and in greater detail in the other figures.

25 A connecting member or extension 4 at one end of the lock is adapted to be attached to a suitable part of the machine or mechanism to be actuated, and this connecting member 4 may in turn be operated by a controlling extension 5 connected with the member 4 through the intermediation of the lock 2. As will be herein- 30 after brought out in greater detail the controlling member 5 is adapted to be selectively adjusted, by any suitable lever or handle 7, to obtain any desired setting of the connecting member or extension 4 and the part which may be connected with it; e. g., an engine throttle, feed adjustment or the like. The lock 2 maintains the adjusted position of the extension 4 until a new setting is made by means of the control 35 lever or handle 7.

As shown in Figs. 1 to 7, the lock comprises a casing, channel or guide 8 containing a plurality of holding or locking members, 10, 11, and 12 adapted to firmly engage with upstanding portions or walls 13 and 14 of the guide 8 to securely retain the locking members in position.

The channel 8 itself may be fixed in any suitable position, depending upon the particular use to be made of it, by screws or bolts 16 extending through apertures at the bottom of the channel 8 and into the plate 1. The holding or locking members are provided with inclined surfaces 10a, 11b, 12a, and 12b adapted to facilitate lateral or transverse move- 50

55

ment of the members into contact with the walls 13 and 14 of the guideway 8, as will be herein-after described in detail. For convenience the holding or locking members may be referred to as wedges and the locking of the members with the walls of the channel 8 may be termed a wedging action. In the preferred embodiment, the outermost locking members or wedges 10 and 11 are shown with their inclined surfaces co-operating with or complementing the inclined surfaces of the intermediate or inner locking member 12; the complementary inclined or wedging surfaces facilitate lateral movement or spreading of the wedge members into gripping engagement with the walls 13 and 14 of the channel member 8. As the right wedge member and intermediate wedge member are pressed toward each other, their complementary inclined surfaces 10a and 12a in effect slide along each other and their side faces or edges move into engagement with the side walls 13 and 14 of the channel member 8; a similar action occurs as the inclined faces 11b and 12b of the left and intermediate wedge member move toward each other. The tighter the wedges are pressed together or toward each other, the more firmly they grip or engage with the wall portions 13 and 14 of the channel member 8, and the more firmly they serve to maintain in position a mechanism with which the lock is connected. While any suitable angle may be used for the inclined faces of the wedges, angles approximately those shown in the drawings have been found to perform satisfactorily in usage.

The wedge members 10, 11 and 12 may normally be urged or pulled toward each other to hold them in an adjusted position within the channel 8 by springs 18 located within recesses 29 of the intermediate wedge 12, the spring being connected with the right and left wedges by connecting members 21 having hook or tab portions 22 at one end thereof and apertures 23 at the other ends thereof fitting over pins 25 carried by the outer wedge members. The springs 18 are held in compressed position by the connecting members 21 so as to normally pull the outer wedge members firmly against the intermediate member; this causes the inclined surfaces of the various members to slide along each other and the side surfaces of the wedge members to grip against the wall portions of the channel or guide 8.

In order to facilitate lateral movement or spreading of the wedge members with respect to each other, to assist in conveying a strain or load to the guide 8, and to minimize any possibility of objectionable jamming, a thin flexible member or ribbon 26 may be secured adjacent the ends thereof to a wall of the guide with an intermediate portion thereof passing between the complementary inclined surfaces of the wedge members. The flexible member or ribbon 26 also minimizes the possibility of one or more of the wedge members being accidentally jarred or moved out of position. The lock may be utilized without the flexible member but its use is preferred since it contributes toward more satisfactory operation of the lock. A thin flexible ribbon of steel has proven quite satisfactory in actual use but a ribbon or cable made of any other suitable material may be used.

From the foregoing description it will be clear that a force applied inwardly in a longitudinal direction against either the right or left wedges 10 and 11 tends to lock or secure the device

more tightly in position within the guide 8. Likewise any force applied to the intermediate or central wedge member 12 in a longitudinal direction also tends to lock the device even more firmly in position. By suitably connecting the wedge members with the extension or connecting member 4 and the controlling extension 5, the slide lock may be utilized to retain the extension or connecting member 4 in any given position, and yet to have the slide lock readily adjustable to a new position by the controlling extension 5.

In Figs. 1 to 7, the connecting member 4 is shown operatively connected with the intermediate wedge 12 by an overlying plate 28 and screw 29. A force applied to the extension arm 4 tending to move it either to the right or to the left (Figs. 1-4) serves only to hold the extension 4 even more firmly in position within the channel due to the gripping action of the wedges with the side walls 13 and 14 of the guide 8.

The slide lock may be made movable along the guide 8 to obtain any desired setting or adjustment by connecting the outer wedges 10 and 11, through bolts 31 and 32, with a substantially U-shaped cover or plate member 34. The plate member 34 is preferably provided with a pair of elongated apertures or slots 35 and 36 extending around the studs or bolts 31 and 32 secured to the outer wedge members 10 and 11. The dimensions and disposition of the slots is such that only their inner edges are adapted to contact with the sides of the bolts 31 and 32 so that as the controlling extension 5 is moved longitudinally toward either the right or left, as shown in Figs. 1 to 4, the effect is to create a pulling tendency on one of the outer wedges 10 or 11. For example, assume the controlling extension 5 is moved to the right (Fig. 4). The inner contracting edge of slot 35 presses against the adjacent side of bolt 31 and pulls right wedge member 10 away from the flexible strip 26, thus tending to separate complementary inclined surfaces 10a and 12a of the right and intermediate wedges. The holding or gripping action between these two wedges is thus overcome and since the intermediate wedge member 12 is connected by the member 21 with the left wedge, the tendency is to move the inclined surface 12b of the intermediate member away from complementary inclined surface 11b of the left wedge member. The connecting member 21 causes intermediate wedge 12 to follow wedge 10 and left wedge 11 to follow wedge 12 when right wedge 10 is moved to the right. Thus the device is unlocked from gripping engagement with the side walls 13 and 14 of guide member 8.

A similar action occurs as the controlling extension 5 is moved toward the left. In this instance the inner edge of the slot 36 contacts the side of the bolt 32 secured to the left wedge member, the left wedge member tends to move away from the complementary inclined surface 12b of the intermediate member, the opposite complementary surface 12a of the intermediate wedge member tends to move away from the co-operating inclined surface 10a of the right wedge member, and the lock is freed for ready movement toward the left. For convenience the controlling extension 5 may be connected to the lever or control arm 7, pivotally secured by a bolt 37 to the plate or mounting part 1.

The plurality of co-operating wedge members, here shown as three in number, forms a compact slide lock and the complementary inclined surfaces give an improved wedging or gripping

action between the sides of the wedges and the walls of the guide 8. An enlarged gripping surface is provided between the side walls 13 and 14 and the large surface area presented by the side edges of the wedge members. The utilization of an intermediate wedge member and connecting the "driven" end of the mechanism to it, provides a construction embodying a minimum of "backlash" or lost motion; the intermediate wedge is locked tight in either direction by the outside wedges so that it immediately tends to resist pressure in either direction.

Figs. 8, 9 and 10 illustrate a slide lock generally similar to that illustrated and described in connection with Figs. 1 through 7, but embodying certain other desirable features. As shown in these figures the slide lock comprises an intermediate wedge 40, holding members 41 and 42, respectively, and a flexible strip member 43 passing between the complementary inclined surfaces of the respective members. A locked member 45 has a pin 46 thereon adapted to fit into an aperture 48 in the intermediate wedge member 40 and a throttle connection or other member 50 to be locked in position may be connected with the locked member 45 by a suitable threaded or other suitable connection 52.

Each of the outwardly disposed left and right holding or wedge members 41 and 42 is adapted to be connected with an unlocking or controlling member 52 through the intermediation of pins 53 and 54 on the latter which project into elongated apertures or slots 56 and 57 of the outer wedge members.

The outer wedge members may be normally urged inwardly toward the intermediate wedge member 40, to thereby facilitate engagement with the side walls of a guideway, by springs 58 and 59 in recesses 61 and 62 of the outer wedge members and retained within the recesses by tab portions or shoulders 64 and 65 adjacent the ends of the unlocking member 52.

The unlocking member 52 may be connected with a control rod or handle by a suitable extension, flexible shaft or other means 67. The lock shown in exploded relationship in Fig. 8 is shown assembled within a tube-like guideway 68 in Fig. 9. The tube-like guideway 68 retains the parts together in assembled relationship and the ends of the flexible member 43 may extend along the tube with tab portions or lugs 69 and 70 projecting around the ends of the tube-like member 68 and secured thereto so as to retain it in operative position at all times.

As brought out in connection with Figs. 1 through 7, the locked member operatively connected with the intermediate wedge member is securely retained in a set or adjusted position at all times. Adjustment of the lock to a new setting may readily be made by moving the controlling extension 67 longitudinally with respect to the tube-like member 68; as the controller member 67 moves the unlocking member 52 toward the left (Figs. 8 and 9) the pin or projection 53 presses against the left side of the elongated slot 56 releases the gripping engagement with the tube walls to facilitate moving the lock to a new position. As the controlling extension 67 is pressed toward the right the pin 54 on the unlocking member 52 presses against the right side of the recess or slot 57 in the right wedge member 42 and pulls the entire slide lock toward the right along through the tube-like member 68.

In Figs. 11, 12 and 13 the slide lock is shown embodied in a controlling mechanism such as a

throttle control of the type useful in connection with the control of aircraft engines. Forms of slide locks which may be utilized with such a throttle control are illustrated in the exploded 5 perspective views of Figs. 13 and 13a. The form illustrated in Fig. 13 comprises an intermediate wedge member 71, outer wedge member 72 and 73, spring members or resilient means 74 and 75 adapted to fit into recesses 76 and 77 of the intermediate wedge member 71, and connecting links 78 and 79 having apertures adjacent one 10 end thereof adapted to fit over pins 80 and 81 of the outer wedge members 72 and 73, and having tab portions at the opposite ends thereof adapted 15 to fit into the recesses 76 and 77 and over the ends of the springs 74 and 75 in such manner as to urge the three wedge members toward each other. The form illustrated in Fig. 13a has the resilient members 74a and 75a located within recesses 76a and 77a provided at the outer ends of the holding or wedge members 72a and 73a. Downwardly extending end or abutment portions 20 of the saddle or cover member 82 may be used to retain the springs 74a and 75a in operative position within the recesses. When assembled with a guideway the projections 91a, 101a and 102a of the wedge member project outwardly through suitable apertures in the cover member 82 and the inwardly extending flanges of a channel or 25 guide member extend through the slots shown at opposite sides of the cover member adjacent the portion where the downwardly extending abutments join with the cover member.

The general constructions are similar to those 30 previously described and they are adapted to fit into and travel along a similar guideway 83 with a flexible strip 84 being secured to the guideway adjacent the ends thereof and passing between the complementary or co-operating inclined surfaces of the wedge members 71, 72, 73 (Fig. 13) or 71a, 72a, 73a (Fig. 13a).

The guideway 83 may be mounted in suitable 35 operating position by screws, bolts or other suitable means to a mounting plate 86. A locked or controlling member or lever 88 may be connected 40 adjacent its lower end with a carburetor, may be pivoted intermediate its ends to the mounting plate 86 by a pin or other means 89, and may have a slot 90 adjacent the upper end thereof 45 fitting about a pin or projection 91 of the intermediate wedge member 71. Thus the pivoted lever or shaft 88 is connected with the intermediate holding wedge of the slide lock so that it will be retained in secured position in a manner similar to that previously described. Preferably the 50 locked lever 88 is provided with an angled or offset portion 93, the reason for which will be clear in connection with the description of the controlling handle 94.

Also mounted on the same pivot or pin 89 which carries the locked lever 88 is the lower part of a controlling or unlocking lever 94 that extends upwardly from the pivot and is provided with widened portions at opposite sides thereof 55 adjacent the slide lock and with an aperture or recess 96 adjacent the slide lock into which may project the offset upper portion of the locked lever 88. The upper part of the lever 94 is shown with a knob 95 to facilitate gripping.

Each side of the outwardly extending portion 60 of the controlling lever 94 is shown with a curved or arcuate surface 98 and 99 located intermediate projections 101, 102 or 101a, 102a of the outer wedges 72, 73 or 72a, 73a, respectively. The 65 springs 74, 75 or 74a, 75a and connecting links

78, 79, or 82 of Fig. 13a, serve to urge the projections toward the curved surfaces 98 and 99 of the controlling lever 94; it has been found that a satisfactory construction is one embodying a very slight amount of clearance or "play" between an inwardly facing surface of a projection 101, 102 or 101a, 102a and a curved surface 98 or 99 of the controlling lever.

This construction insures secure retention of the slide lock and locked member 88 in a set position within the guideway 83 and yet facilitates ready adjustment to a new position upon movement of the controlling knob 95 and controlling lever 94 toward the left or right (Fig. 11). As the controlling lever 94 is moved toward the left in Fig. 11 the curved surface 98 presses outwardly against the inner side of the projection 101 or 101a and is effective to overcome the resilient effect of the slide lock springs, to permit movement of the entire lock toward the left; as the wedge member 72 or 72a is thus moved toward the left the intermediate wedge member 71 or 71a and right wedge member 73 or 73a follow along through the guideway 83. The locked lever 88 may thus be moved to a new setting. A similar action occurs as the knob 95 and unlocking lever 94 is moved toward the right.

A cover plate 105 may be secured over the operating parts of the throttle control by screws or bolts 106 and the levers 89 and 94 may be maintained in operative position closely adjacent the slide lock by spacers or washers 107. An arcuate shaped cover plate 108 provided with a slot 109 may be fitted between the mounting plate 86 and cover plate 105 to minimize entry of foreign objects into the slide lock.

In Fig. 14 there is illustrated a modified form of the invention, having one or more spring members 111 and 112 connecting an intermediate wedge with the right and left wedge members. This construction may be preferable in certain instances to the connecting members 24 and springs 18 described in connection with Figs. 1-7. The lock of the form shown in Fig. 14 may be connected with a suitable connecting extension and controlling extension similarly to the embodiment of Fig. 1-7.

In Fig. 15 the slide lock is shown adapted to travel along an arcuate or curved path. A curved guide member 114 has therein outer wedge members 116 and 117 and an intermediate wedge member 118 having curved outer sides adapted to move firmly into frictional engagement with the side walls 119 and 120 of the guide channel 114. A flexible strip 122 is shown passing between the complementary surfaces of the wedge members and secured adjacent the ends thereof to a side wall of the guide member. The right and left wedge members 116 and 117 are provided with pins 123 and 124 to which are secured the ends of resilient members or springs 125 effective to normally urge the outer wedge members toward the intermediate wedge; the opposite ends of the springs 125 are shown secured to projections 127 of an extension arm 128 pivotally secured by a bolt 130 to the plate 126 which is in turn adjustably connected with the intermediate wedge 118 by a screw or bolt 129.

One end of the extension arm 128 may be connected by a lever portion 131 with the mechanism to be held in position by the slide lock; the opposite portion 132 of the extension arm 128 preferably projects into an opening 134 of a control arm 135 which is pivoted adjacent its lower part by the bolt or screw 130 to the mount-

ing plate 126. The control arm 135 has connected therewith laterally extending portions 137 and 138 having elongated apertures or slots 140 adjacent the outer ends thereof through which project the pins 123 and 124 of the outer wedge members 116 and 117. As the controlling arm or extension 135 is moved toward the right or left (Fig. 15) the inner edges of the slots 140 press against the pins 123 or 124 of the right or left wedges, depending upon the direction in which the arm 135 is moved, and are effective to shift the slide lock wedges as a unit to a new desired position. Since the extension arm 128 is secured to the intermediate wedge 118, any force applied adjacent the lower part of the extension arm tending to move it out of an adjusted position serves only to clamp or engage the locking wedges more firmly in their set position. A cover plate 139 (Figs. 16 and 17) may be secured over the operating parts by bolts threaded into apertures 141.

It will be understood that a locking device of the type described in connection with Figs. 1 through 13 may be utilized instead of the curved form of Figs. 15, 16 and 17. However the latter device offers certain advantages in some instances.

The wedging or locking members hereinabove described may be cut or formed from suitable bar stock, may be formed by casting operations, or they may be manufactured by securing together several thicknesses of sheet material to form a laminated wedge of the type illustrated in Fig. 18. The separate thicknesses or laminations 142 of the wedge shown in Fig. 18 may be more readily stamped out by punch presses and thereafter secured together by spotwelding or by pinning them together through the apertures 143 formed during the stamping operations. Any type of wedge member performs satisfactorily in actual usage.

It will be seen that the present invention provides a new and improved slide lock which is adapted to securely maintain in adjusted position a mechanism with which it is operatively connected. While the slide lock holds a throttle, feed mechanism or the like, securely in a set position it may be readily adjusted to a new setting by a control rod or handle connected therewith. The slide lock of the present invention is of relatively simple construction, possesses few parts and is readily adapted to withstand any rough usage to which it may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, the combination of a pair of radially spaced opposed curved walls forming a curved guideway, a plurality of members having complementary inclined end surfaces and having exterior surfaces shaped to conform substantially to the curvature of said radially spaced curved walls and slidable therealong, yieldable means normally urging said members together to thereby effect movement of said inclined surfaces with respect to each other and engagement of the members with curved portions of said guideway walls, and means for selectively positioning said members with respect to said guideway.

2. In a device of the class described, the combination of a curved guideway, a plurality of members having complementary relatively movable spreader surfaces and having exterior surfaces shaped to conform substantially to the curvature of said guideway, an elongate flexible member connected adjacent opposite ends thereof with said guideway at one side thereof and extending between said spreader surfaces, yieldable means normally urging said members together to thereby effect gripping of the members against portions of said guideway, and means for selectively positioning said members with respect to said guideway.

3. In a device of the class described, the combination of a guide comprising radially spaced opposed walls each having a substantially arcuate form and said walls forming an opening of uniform cross-section, a plurality of members associated with said guide having arcuate surfaces in engagement with one of said walls and having inclined wedging surfaces, an additional member located interiorly with respect to said first mentioned members having an arcuate surface in engagement with another of said walls and having inclined wedging surfaces facing toward and adapted to co-operate with the inclined surfaces on said first members, and means normally urging said members toward each other to effect engagement of the members with portions of said guide.

4. In a device of the class described, the combination of a channel having a substantially uniform effective width and radially spaced opposed walls of arcuate form, a plurality of members associated with said guide having inclined end surfaces and substantially arcuate side portions movable along an arcuate wall, an additional member located interiorly with respect to said first mentioned members having inclined surfaces facing toward and adapted to co-operate with the inclined surfaces on said first members and also having a substantially arcuate side portion thereafter movable along an arcuate wall, and means normally urging said members toward each other to effect engagement of the members with arcuate wall portions of said guide.

5. In a device of the class described, the combination of a guide having radially spaced opposed walls of substantially arcuate form, a plurality of members associated with said guide having inclined spreader surfaces and arcuate wall-engaging surfaces, an additional member located interiorly with respect to said first mentioned members having inclined spreader surfaces adapted to co-operate with the inclined surfaces on said first members and having a wall engaging surface, means normally urging said members toward each other to effect lateral spreading and engagement of the arcuate surfaces of the members with arcuate portions of said guide walls, an arm operatively connected with said interiorly located member adapted to be retained in a set position by said device, and means operatively connected with said first mentioned members for changing the position of said device and establishing a different setting of said arm.

6. In a device of the class described, the combination of a tubular enclosing guide, a plurality of co-operating members enclosed within and movable through said guide having opposed inclined faces forming wedging surfaces, and having faces engageable with one wall of the tubular

guide, an additional member having inclined faces forming wedging surfaces and having a face engageable with an opposite wall of the guide, a flexible member operatively secured to the guide at spaced points and extending between the inclined faces of said members, yieldable means normally urging said members into engagement with the flexible member, and into engagement with opposite walls of the tubular guide and means operatively connected with said members for releasing engagement with walls of the tubular guide and facilitating adjustment thereof.

7. In a device of the class described, the combination of a guide including spaced wall portions, a central wedge member having oppositely outwardly facing inclined surfaces and a face slidable along one of said wall portions, an elongate flexible member connected at spaced locations with said wall portion along which the central wedge member is slidable and extending over said oppositely outwardly facing inclined surfaces, a plurality of wedge members having inwardly facing inclined surfaces adapted to press the flexible member against the oppositely outwardly facing inclined surfaces of said central wedge member, yieldable means normally urging said wedge members toward each other to grip said flexible member between the co-operating inclined surfaces, a member connected with said central wedge member against relative movement along the guideway with respect thereto adapted to be retained in an adjusted position, and means for selectively positioning the wedge members with respect to the guide.

8. In a device of the class described, the combination of a guide having substantially parallel wall portions, a central wedge member having outwardly facing inclined surfaces, a flexible member connected with the guide at spaced locations and extending over said inclined surfaces, a plurality of outwardly disposed wedge members having inclined surfaces adapted to press the flexible member against the outwardly facing inclined surfaces of said central wedge member, yieldable means normally urging said wedge members toward each other to grip said flexible member between the co-operating inclined surfaces, a pivotally mounted member connected with said central wedge member against end-play along the guide and normally fixedly retained in an adjusted position, and a pivotally mounted member operatively connected with said outer wedge members for selectively positioning the wedge members with respect to the guide.

9. In a device of the class described, the combination of a guide, a central wedge member having outwardly facing inclined surfaces, a flexible member connected with the guide at spaced locations and extending over said inclined surfaces, a plurality of outwardly disposed wedge members having inclined surfaces adapted to press the flexible member against the inclined surfaces of said central wedge member, projections on said outer wedge members extending out of the plane thereof, yieldable means normally urging said wedge members toward each other to grip said flexible member between the co-operating inclined surfaces, a pivotally mounted member connected with said central member adapted to be retained in an adjusted position, and a second pivotally mounted member having surfaces adapted to press against the projections of said outer wedge members in the general direction of

11

movement of said second pivotally mounted member upon movement thereof to selectively position the wedge members with respect to the guide.

10. In a device of the class described, the combination of a guideway including spaced wall portions, a plurality of spaced members in said guideway engageable with a wall thereof, each having an inclined spreader surface and provided with an outer end portion substantially filling the space between said wall portions, an additional member in said guideway intermediate said spaced members engageable with a wall of said guideway and having inclined spreader surfaces adapted to complement said first mentioned inclined spreader surfaces with end portions thereof terminating intermediate the outermost ends of said spaced members, and yieldable means normally urging said members together to thereby effect engagement of the members with said wall portions of the guideway.

11. In a device of the class described, the combination of a guideway, a plurality of wedging members engagable with said guideway having inclined spreader surfaces, an additional wedging member intermediate two of said first mentioned members having inclined spreader surfaces adapted to complement said first mentioned inclined spreader surfaces and having a surface engageable with said guideway, a flexible member connected with the guideway and extending between said inclined spreader surfaces, and means for shifting the position of said spreader surface members.

12. In a device of the class described, the combination of a guideway having spaced walls, a plurality of outwardly disposed wedge members in said guideway having inclined surfaces, an additional wedge member in said guideway between said outer wedge members having inclined surfaces adapted to co-operate with the inclined surfaces of said outer wedge members to lock and unlock the members with walls of the guideway, a flexible member connected at spaced locations thereon with one of said guide-

12

way walls and extending between said co-operating inclined surfaces of the wedge members, and means for shifting the position of said wedge members along the guideway.

5. 13. In a device of the class described, the combination of a guideway including spaced wall portions, an inner member in said guideway slideable along one wall thereof having inclined wedging surfaces thereon, an outer member in said guideway adjacent each end of said inner member slideable along another wall thereof each having an inclined wedging surface facing toward and co-operating with the inclined surfaces of said inner member to lock said members to walls of the guideway and each having an outermost end portion located beyond outermost end portions of said inner member, a flexible member in said guideway connected at spaced locations with said wall along which the inner member is slideable and extending between said co-operating inclined surfaces of the inner and outer members, yieldable means urging said inner and outer members toward each other and against said flexible member, and means for moving said inner and outer members along said flexible member and said guideway.

LOUIS L. DEAL.
